Primary Examiner — Natasha Vujevic(74) *Attorney, Agent, or Firm* — Vincent G. Lo Tempio(57) **CLAIM**

The ornamental design for an ultraviolet light housing, as shown and described.

DESCRIPTION

FIG. 1 is a top perspective view of an ultraviolet light housing showing my new design.

FIG. 2 is a top view thereof;

FIG. 3 is a bottom view thereof;

FIG. 4 is a left side view thereof;

FIG. 5 is a right side view thereof;

FIG. 6 is a back view thereof;

FIG. 7 is a front view thereof; and,

FIG. 8 is a bottom perspective view thereof.

The broken lines in the drawings illustrate portions of the ultraviolet light housing which forms no part of the claimed design.
